SOAP CAKE

Theodore Backen, Brooklyn, N. Y.

Application July 10, 1934, Serial No. 734,453

2 Claims. (Cl. 87—23)

This invention relates to new and useful improvements in soap cakes, and has for its object to provide a cake of soap, composed of different kinds of soap, and having such different kinds arranged in a specific and novel manner for new and useful purposes.

Thus, according to my invention, two, or more, kinds of soap may be combined in one soap cake, for instance, by having one end of the cake consisting of a soft and oily soap of the quality usually employed for the face and hands, or, if desired, a quality, especially suitable for babies, and the other end of the cake consisting of a soap, especially adaptable for scrubbing and scouring purposes, and having the characteristics of a pumice.

In addition, there is in this invention contemplated the arrangement of features to the effect that several pieces of soap, of a certain quality, may together, or in turn be separated from a main body of soap of a different quality; or the said several pieces may, when having the characteristics of a pumice, be so arranged, relative to the other kind of soap, constituting the assembled device, that said several pieces of soap may serve as a scouring medium, somewhat similar to a scrubbing brush, or cleaner.

Finally, the novel combination and relative arrangement of the different kinds of soap, as hereinbefore stated, may, it is thought, be usefully employed by some concern, for instance, a combination of chain stores, especially in the grocery line, for advertising purposes.

As the manufacture, according to the disclosure herein, would be comparatively simple, the cost should normally be as low, as in the ordinary manufacturing of soaps.

With the above and other objects in view, this invention consists of the novel features of construction, combination and arrangement of parts, hereinafter fully described, claimed, and illustrated in the accompanying drawing forming parts of this specification, and in which similar characters of reference indicate corresponding parts in all views, and in which:—

Figure 1 is a side elevational view of my invention.

Figure 2 is a transverse sectional view, taken on the line 2—2 in Figure 1; while

Figure 3 shows a modification of my invention, as herein described.

Referring more particularly to the drawing, 10 indicates a piece of soap of the kind commonly used for the face and hands; while 11, 11 indicate several pieces of soaps, of one or more dif-

ferent kinds; the latter pieces being in the process of manufacturing slightly connected together in such a manner that any of these pieces may easily be broken away from the one at its side; this latter step is mainly accomplished by connecting the central body portion of said pieces together, and at the same time having a comparatively deep recess or groove between the edges of said pieces; said groove being indicated by the numeral 12.

The pieces 11, 11 are in a similar way connected to the piece of soap 10, a slightly deeper recess 13 is, however, formed between the piece 10 and the nearest one of the pieces 11, in order that the latter, as a unit, may be broken away from the said piece 10, if this should be desired.

In order, however, to assure that upon separation of the coarser soap, or scouring soap, from the toilet soap, the latter will under all circumstances be free from any trace or particles of said scouring soap, the somewhat deeper recess 13 is formed in the toilet soap 10 to the effect that a slight piece or rim 14 of the toilet soap is closely associated with the said scouring soap pieces 11, and will be broken off with the latter upon separation of these from the toilet soap 10.

In Figure 3 is shown a modification of my device to the effect that the pieces 11, 11 are connected in an endwise manner to the main body, or piece 10.

The latter arrangement will serve the purpose of providing a scouring medium, somewhat similar in effect to a scouring brush, while after having applied said medium to a greasy object the person may clean his hands by means of the toilet soap 10.

It is naturally to be understood that also in the modified form of the invention the pieces 11, 11, may be singly or together separated from the main piece of soap 10.

The relative connection of the soap pieces 11, 11 to the soap piece 10 with reference, especially, to the rim portion 14, is maintained in the modification shown in Figure 3.

I claim:

1. In an article of manufacture, a cake of soap, comprising two sections, one section of a toilet soap quality, and the other section of a scouring soap quality, said two sections being separated by means of a groove of a substantial depth arranged in the soap section of the toilet quality, the wall of the groove adjoining the section of the scouring soap quality being also of the soap section of the toilet quality, the section of the scouring soap quality consisting of a plurality of pieces transversely arranged with respect to the section 45
- 50
- 55

of the toilet soap quality and at the end of the latter, said pieces being partly separated from one another by means of grooves among the latter, thereby imparting to the said pieces a brush-bristle like appearance and effect, when viewing the two sections together, and permitting the separation individually of said scouring soap pieces.

2. In an article of manufacture, a cake of soap, comprising two sections, one section of a toilet soap quality and being of a substantially rectangular shape, and the other section of a scouring soap quality, the latter having its body portion

formed in an accordion-like manner, said two sections being separated by means of a groove of a substantial depth arranged in the soap section of the toilet quality, the wall of the groove adjoining the section of the scouring soap quality being also of the soap section of the toilet quality, the accordion-like shaped portion comprising pieces partly separated from one another by means of grooves therebetween, thereby permitting separation individually of said scouring soap pieces.

THEODORE BACKEN.
